United States Patent Office

Des. 194,089
Patented Nov. 13, 1962

194,089

COUPLING FOR PIPES OR THE LIKE

Alfred Nilsen, Hanford, Calif., assignor to Sawtelle & Rosprim, Corcoran, Calif., a partnership

Filed Apr. 21, 1961, Ser. No. 64,849

Term of patent 14 years

(Cl. D91—3)

FIG. 1.

FIG. 2.

FIG. 3.

FIG. 4.

FIG. 1 is a perspective front view of the coupling for pipes or the like showing my new design.

FIG. 2 is a rear elevation thereof as seen from the opposite side of FIG. 1;

FIG. 3 is a side elevation thereof as seen from the left of FIG. 2;

FIG. 4 is a top plan view thereof.

I claim:

The ornamental design for a coupling for pipes or the like, as shown.
